UNITED STATES PATENT OFFICE.

HUGO KLEINEICK, OF NEWARK, NEW JERSEY.

DESIGN FOR A VIOLIN-CASE.

SPECIFICATION forming part of Design No. 19,736, dated April 1, 1890.

Application filed March 3, 1890. Serial No. 342,496. Term of patent 14 years.

To all whom it may concern:

Be it known that I, HUGO KLEINEICK, a subject of the Emperor of Germany, residing at Newark, Essex county, New Jersey, have 5 invented a certain new and useful Design for Violin-Cases, fully described and represented in the following specification and the accompanying drawings, forming a part of the same.

10 This design relates to a violin-case wider at one end than the other, in correspondence with the different widths of the body and head of a violin, and in which the opposite sides are substantially flat where united to the edges.

15 The design consists in a violin-case having substantially flat sides, with a swell upon each of the flat sides, near the wider end of the case, and a swell upon the bottom only, 20 near the narrower end or head of the case.

In the annexed drawings, Figure 1 is an edge view of the violin-case, and Fig. 2 is a perspective view of the same with the bottom turned upward.

In Fig. 1 the case is shown with the top 25 side up and the wide or body end at the right hand, *a* being the top and *b* the bottom of the case. *c* is the swell or protuberance upon the bottom at the wider part of the same, and *d* is the swell, of smaller dimensions, upon the 30 bottom, at the narrow part of the case. *e* is the swell upon the top *a*, opposite the swell *c*.

In Fig. 2 the case is shown with the wider end at the left hand and the bottom end turned upward, thus exhibiting the swells *c* 35 and *d* only.

What I claim is—

The design for a violin-case having a shape comprising the substantially flat top and bottom provided with the swells *c*, *d*, and *e*, substantially as herein set forth.

In testimony whereof I have hereinunto set my hand in the presence of two subscribing witnesses.

HUGO KLEINEICK.

Witnesses:

L. LEE,
THOS. S. CRANE.
